Primary Examiner — Steven J Czyz*(74) Attorney, Agent, or Firm* — Fay Sharpe LLP(57) CLAIM

The ornamental design for a shelf liner, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is an enlarged view of a top surface of the shelf liner; and

FIG. 2 an enlarged view of a bottom surface of the shelf liner.

FIG. 3 is a top view of the shelf liner; and,

FIG. 4 is a bottom view of the shelf liner.

The broken lines and area depicted therebetween form no part of the claimed design. The grey color of the shelf liner is part of the claimed design.
